(57) **CLAIM**

The ornamental design for a cart, as shown and described.

DESCRIPTION

FIG. 1 is a front perspective view of a cart showing our new design, with the cover trays removed.

FIG. 2 is a side elevation view of the right and left sides, which are mirror images, of FIG. 1.

FIG. 3 is a front side elevation view of FIG. 1.

FIG. 4 is a back side elevation view of FIG. 1.

FIG. 5 is a top plan view of FIG. 1.

FIG. 6 is a bottom plan view of FIG. 1.

FIG. 7 is a side elevation view of the right and left sides, which are mirror images, of the embodiment of FIG. 1 with the only difference being the top shelf is in an upright position, the bottom cover being lifted to the nesting position and the storage rack in a stowed position, it being understood that all other surfaces are the same as the other views of this embodiment.

FIG. 8 is a front perspective view of the embodiment of FIG. 1 with the only difference being cover trays are placed, it being understood that all other surfaces are the same as the other views of this embodiment.

FIG. 9 is a side elevation view of the right and left sides, which are mirror images, of FIG. 8.

FIG. 10 is a front side elevation view of FIG. 8.

FIG. 11 is a back side elevation view of FIG. 8.

FIG. 12 is a top plan view of FIG. 8; and,

FIG. 13. is a bottom plan view of FIG. 8.

The features shown in broken lines in the drawing depict environmental subject matter only and form no part of the claimed design.
